United States Patent Office

Des. 183,183
Patented July 8, 1958

183,183

AIRPLANE

Milton J. Schmidt, Sacramento, Calif.

Application May 29, 1957, Serial No. 46,409

Term of patent 14 years

(Cl. D71—1)

FIG. 1—

FIG. 2—

FIG. 3—

Figure 1 is a top plan view of an airplane showing my new design;

Figure 2 is a side elevational view thereof; and

Figure 3 is a front elevational view.

The dominant features of the design reside in the portions shown in full lines.

I claim:

The ornamental design for an airplane, substantially as shown and described.
